Filed Nov. 12, 1973, Ser. No. 414,967

Term of patent 14 years

Int. Cl. D6—99

U.S. Cl. D6—28

FIG. 1 is a perspective view of a pole rack showing my design;

FIG. 2 is a plan view;

FIG. 3 is a perspective view looking in the direction opposite that of FIG. 1;

FIG. 4 is a bottom plan view thereof;

FIG. 5 is a bottom plan view of the rack of FIG. 1 wherein the support rods are attached to one side of the vertical pole member;

FIG. 6 is a bottom plan view of the rack of FIG. 1, but wherein the support rods are attached to three sides of the vertical pole member;

FIG. 7 is a bottom plan view of the rack of FIG. 1 wherein the support rods are attached to all four vertical faces of the pole member; and

FIG. 8 is a perspective view of another modified form of the rack of FIG. 1 wherein the number of support rods is varied, and the top of the spring member is square rather than round.

I claim:

The ornamental design for a pole rack, substantially as shown and described.
